Primary Examiner — Elizabeth Albert

(74) Attorney, Agent, or Firm — Endurance Law Group,
PLC(57) **CLAIM**

I claim the ornamental design for a planter assembly, as shown and described.

DESCRIPTION

FIG. 1 is an assembled perspective view of a planter assembly showing my new design;
FIG. 2 is an exploded perspective view thereof;
FIG. 3 is an exploded front elevation view thereof;
FIG. 4 is an exploded rear elevation view thereof;
FIG. 5 is an exploded left side view, with the right side view being a mirror image thereof;
FIG. 6 is an exploded top thereof; and,
FIG. 7 is an exploded bottom view thereof.
